ABSTRACT OF THE DISCLOSURE

Electrothermal timing apparatus is disclosed in which a plurality of pairs of thermistors pass through electrothermal cycles in sequence. In each pair the thermistors are of opposite temperature coefficient types and are interconnected in a circuit such that heating of one of the thermistors will initiate an electrothermal cycle in which one and then the other of the thermistors pass through self-heating phases in sequence. Successive pairs are thermally coupled so that the occurrence of an electrothermal cycle in one pair will initiate a similar cycle in a subsequent pair.

This invention relates to electrothermal timing apparatus, and more particularly to such apparatus which is suited for determining relatively long periods.

It has heretofore been known to employ thermistors for timing purposes and to use pluralities of electrically interconnected thermistors for obtaining oscillatory or sequencing functions. However, in these known constructions, the heat dissipated from the thermistors is typically treated only as a power loss. While the heat losses are accounted for in that they interrelate with and determine the electrical characteristics of the thermistors, the losses are themselves not employed for any useful purpose. In many of the prior art sequencing devices in which pluralities of thermistors were interconnected, each stage typically had to be operated at a lower power level than the one preceding it, since each stage drew its electrical power through the preceding stage.

Among the several objects of the present invention may be noted the provision of novel electrothermal timing apparatus employing self-heating thermistors for obtaining a time delay; the provision of such apparatus in which the heat resistively dissipated in at least some of the thermistors is usefully employed to effect signal coupling between successive timing stages; the provision of such timing apparatus in which successive stages may be operated at similar power levels; the provision of such apparatus in which successive stages may be electrically isolated; the provision of such timing apparatus which is suited for determining relatively long periods; the provision of such apparatus in which such successive stages may operate at widely dissimilar time intervals; the provision of such timing apparatus which can time programming functions; the provision of such timing apparatus which can be constructed simply and inexpensively; and the provision of such timing apparatus which is highly reliable. Other objects will be in part apparent and in part pointed out hereinafter.

Briefly, electrothermal timing apparatus of this invention involves a plurality of pairs of thermistors. One of the thermistors in each of the pairs is of a first temperature coefficient type and the other is of the opposite temperature coefficient type. The thermistors in each pair are interconnected with each other to provide electrical coupling therebetween and the different pairs of thermistors are interconnected with an electric power source whereby heating of the thermistor of the first coefficient type in one of the pairs will initiate an electrothermal cycle in which the one and then the other of the thermistors in

that one pair pass through self-heating phases in sequence. The thermistor of the opposite coefficient in at least one of the pairs is thermally coupled to the thermistor of the first coefficient type in another one of the pairs whereby the occurrence of an electrothermal cycle in the one pair of thermistors initiates an electrothermal cycle in the other pair of thermistors.

The invention accordingly comprises the constructions hereinafter described, the scope of the invention being indicated in the following claims.

In the accompanying drawings in which several of various possible embodiments of the invention are illustrated:

FIG. 1 is a schematic circuit diagram of electrothermal timing apparatus of this invention employing a plurality of pairs of thermistors, each pair of which includes a PTC and an NTC thermistor;

FIG. 2 is a graph representing the changes in resistance of the PTC thermistors with respect to changes in temperature;

FIG. 3 is a graph similarly representing the changes in resistance of the NTC thermistors with respect to changes in temperature;

FIG. 4 is a graph representing the current/voltage behavior of the PTC thermistors;

FIG. 5 is a graph representing the voltage/current behavior of the NTC thermistors;

FIG. 6 is a schematic circuit diagram of a modification of the thermistor timing apparatus of FIG. 1;

FIG. 7 is a side view of a thermistor pair construction suited for use in the apparatus of FIG. 6;

FIG. 8 is a top view of the thermistor pair construction of FIG. 7; and

FIG. 9 is a schematic circuit diagram of electrothermal timing apparatus employing pairs of thermistors in which the pairs are connected in series.

Corresponding reference characters indicate corresponding parts throughout the several views of the drawings.

Referring now to FIG. 1, the timing apparatus illustrated there includes a plurality of pairs (11-18) of thermistors. Each pair comprises a bistable switching stage and includes one thermistor having a positive temperature coefficient (PTC) of resistivity, P11-P18 respectively, and a second thermistor having a negative temperature coefficient (NTC) of resistivity, N11-N18 respectively. All of the thermistors may, for example, be deposited on a common substrate by known thick film techniques. The PTC thermistor and the NTC thermistor constituting each pair are connected in series with each other across a pair of supply leads L1 and L2 through which electrical power at substantially constant voltage is supplied to the apparatus. Since the thermal behavior of the various thermistors is governed essentially by the power dissipated therein, direct current of either polarity may be applied to the leads L1 and L2 or alternating current of equivalent RMS voltage may be used.

A PTC triggering thermistor PT1 is connected across leads L1 and L2 through a circuit which includes a current limiting resistor R1 and a normally open push-button switch PB1. When switch PB1 is closed thermistor PT1 heats to its transition temperature. Thermistor PT1 functions as an external heater and is thermally coupled to NTC thermistor N11 as indicated by the dotted line linking the two thermistors. Thus, by closing switch PB1, thermistor N11 can be heated by thermistor PT1.

The PTC thermistors P11-P17 of the pairs 11-17 are thermally coupled to the NTC thermistors N12-N18 respectively in the pairs 12-18 as indicated by the dotted lines enclosing the respectively coupled thermistors. This coupling may, for example, be provided by electrically insulated metallic strips. Thus, if PTC thermistor P11 self-

heats, heat will be applied to NTC thermistor N12 by conduction through the thermal coupling.

Preferably, the PTC thermistors P11-18 are of the type having a sharply defined transition temperature above which the thermistor material's resistance increases sharply. An example of a material which possesses such a resistance characteristic is doped barium titanate (BaTiO_3). The behavior of the resistance of this material is represented in FIG. 2 with respect to changes in temperature, the transition temperature being indicated on the temperature scale at TR.

Thermistors constructed of this material have an equilibrium current/voltage characteristic, as illustrated in FIG. 4, which has a pronounced negative resistance region as indicated at NRP, that is, the equilibrium current passing through the thermistor decreases with increasing voltage levels above a predetermined threshold. As is understood by those skilled in the art, devices having negative resistance characteristics are capable of being connected in circuits for producing bistable switching. It should be understood that the curves of FIGS. 4 and 5 represent the behavior of the respective thermistor element when it has sufficient time to come to equilibrium under a given set of ambient conditions and that the shape and size of the curve may be altered by varying the ambient conditions as, for example, by applying heat to the thermistor element.

The resistance characteristics of the NTC thermistors N11-N18 are represented in the graph of FIG. 3. As may be seen, the resistance decreases in a gentle curve with increasing temperature. The voltage/current characteristic of the NTC thermistors N11-N18 is represented in the graph of FIG. 5. As may be seen, the NTC thermistors N11-N18 also have a negative resistance region as indicated at NRN in which the voltage across the thermistors falls with increasing current above a predetermined threshold. This negative resistance region is, however, typically not as large nor as steep as that possessed by the PTC thermistors. It should be noted that the voltage and current scales have been reversed in FIG. 5 as compared with FIG. 4. It may thus be seen that the NTC thermistors are, in certain respects, current analogs of the voltage characteristics of the PTC thermistors.

While NTC thermistors having gently sloped resistance characteristics and PTC thermistors having steeply sloped characteristics are illustrated herein by way of example, it should be understood that steep slope NTC and shallow slope PTC thermistors may also be employed under various conditions.

When thermistors having opposite temperature coefficients of resistivity are connected in series across a source of substantially constant voltage, electrical interaction between the two thermistors is obtained. Such series-connected thermistors are essentially voltage coupled in that, if the voltage across one of them changes, the voltage across the other must change in complementary fashion. In the apparatus illustrated in FIG. 1, the voltage applied to the leads L1, L2 is selected in relation to the characteristics of the particular thermistors to obtain a bistable or two-state switching mode of operation in which one and then the other of the thermistors in a pair pass through self-heating phases when that pair is triggered.

While a theory of operation for the thermistor pairs has not been completely developed, the following explanation has been found useful in understanding and working with these constructions. Thermistor pair 11 is taken as an example. Initially both the PTC thermistor P11 and the NTC thermistor N11 are relatively cool. The PTC thermistor P11 thus has a relatively low resistance while the NTC thermistor N11 has a relatively high resistance. Accordingly, only a relatively small portion of the supply voltage appears across the PTC thermistor P11. Although a relatively large portion of the supply voltage thus appears across the NTC thermistor N11, only a relatively small current flows through the series-con-

nected pair due to the relatively high resistance of the NTC thermistor. In this state both of the thermistors are outside of their negative resistance regions and the pair is stable in this initial equilibrium condition.

If, however, heat is applied from an outside source to the NTC thermistor N11, as by means of the triggering thermistor PT1, this heating has the effect of lowering the peak in the equilibrium NTC voltage/current characteristic and NTC thermistor N11 thus passes into its negative resistance region at the applied voltage. If NTC thermistor N11 is triggered in this way, it self-heats and tends to seek a new equilibrium at a higher temperature as determined by the electrical load in series with it. However, as NTC thermistor N11 self-heats toward the new equilibrium which it would acquire if its series load remained constant, the effect of this self-heating is to lower the resistance of the NTC thermistor N11 causing an increased portion of the source voltage to be applied to the series-connected PTC thermistor P11. The higher voltage applied to the PTC thermistor P11 causes it to pass into its negative resistance region and to begin a self-heating phase also. The load in series with the NTC thermistor N11 thus does not remain constant.

The heat generated by the self-heating of PTC thermistor P11 is coupled to the NTC thermistor N12 in the adjacent pair of thermistors 12 so that it also begins to self-heat. In addition to starting a bistable switching cycle in the thermistor pair 12, the self-heat then generated by NTC thermistor N12 is coupled back to PTC thermistor P11 and the resultant total heat increases the resistance of PTC thermistor P11 to an extent which sharply reduces the current flowing through the series-connected pair 11.

This drop in current causes the NTC thermistor N11 to stop its self-heating action and to revert to its original, relatively cool equilibrium condition in which it exhibits a high resistance. The increased resistance of the NTC thermistor N11 further reduces the current through the series circuit 11 so that the PTC thermistor P11 also then passes out of its negative resistance region and reverts to its original, relatively cool equilibrium state. With both thermistors in their stable states, the circuit 11 is effectively reset and will remain quiescent until the NTC thermistor is again triggered either by the application of external heat as described above or by some other method. In the meantime a cycle of bistable electrothermal switching has been initiated in the thermistor pair 12. During the switching cycle of the thermistor pair 12, the self-heating phase of PTC thermistor P12 will initiate a bistable cycle of operation in the thermistor pair 13 which in turn initiates a similar cycle in pair 14, etc. Thus it can be seen that a string of bistable switching operations is propagated down the plurality of thermistor pairs or stages, each successive cycle being delayed in time with respect to the preceding cycle. The time required for completion of each bistable switching cycle is determined by the thermal inertia and dissipation characteristics of the thermistors which make up the pair. However, it may in general be noted that the periods required are typically much longer than those encountered or practically obtainable in wholly electronic components of similar size. Further, the time periods can vary over a wide range from stage to stage in the same apparatus.

Since the triggering of each successive pair or stage by the preceding stage is provided by thermal coupling between the stages, it can be seen that all of the stages can operate at essentially the same power level or that a low power stage may even trip a somewhat higher powered stage. Further, the stages which are thermally coupled may be electrically isolated from one another and powered from different sources.

The sequence of operations provided by the apparatus of FIG. 1 will repeat continuously if the stages are coupled to form a loop in which each stage in the loop triggers a following stage. In the apparatus of FIG. 1, an

NTC thermistor N11A is thermally coupled to PTC thermistor P18 and can be electrically connected in parallel with the NTC thermistor N11 by means of switch SW1. When NTC thermistor N11A is thus connected into the circuit, it can take the place of thermistor N11 in bistable switching with the PTC thermistor P11. PTC thermistor P11 can thus function in its switching mode with either of the NTC thermistors N11 or N11A and triggering of such switching operations can be initiated by externally applying heat to either thermistor N11 or thermistor N11A. Since the quiescent or stable state for thermistors N11 and N11A is the cool or high resistance state, that one of the two NTC thermistors which is not functioning in a switching cycle with PTC thermistor P11 does not appreciably load or affect the switching operation involving the other. A sequence of switching operations started by closing push-button PB1 will thus continue indefinitely when the switch SW1 is closed. When the sequence of operations reaches the thermistor pair 18, the heating of PTC thermistor P18 will apply heat to the NTC thermistor N11A, thereby triggering another complete sequence of operations. This repetitive cycle of operations continues indefinitely until it is stopped by opening the switch SW1, thereby breaking the loop by severing the connection between NTC thermistor N11A and PTC thermistor P11 which provides a predetermined point of interruption of the sequence.

As the various thermistor pairs 11-18 operate in timed succession, it can be seen that the apparatus of FIG. 1 is suited for controlling operations which are to be performed in a given sequence. The occurrence of any or all of the successive steps within the overall sequence of electrothermal cycles may be sensed in various ways for control or signalling purposes. As the current flowing through each series-connected pair of thermistors varies during its switching cycle of operation, the occurrence of such an operation may be detected by current-sensing means connected in series with the thermistors. A particularly simple such current sensor is a low resistance incandescent lamp such as those indicated at 21 and 23 in the thermistor pairs 14 and 18. Lamps 21 and 23, being of low resistance, do not appreciably affect the switching mode of operation of the series pairs as described previously.

As the voltage across either one of the constituent thermistors in each series-connected pair varies as the pair goes through its switching cycle of operation, such a cycle of operation may also be detected by sensing the voltage across one of the thermistors. A particularly simple form of voltage-sensing device is a high resistance incandescent bulb such as indicated at 25 connected across the NTC thermistor N16 in thermistor pair 16. Being of high resistance, lamp 25 does not appreciably load or interfere with the operation of the thermistor pair 16 but will vary in brightness as the switching progresses. Lamps such as 21, 23 and 25 may be used for visual indication of the sequencer's progress or, by driving suitable photo-sensitive devices, may be used for programming or controlling outside operations which are to be performed in sequence.

The occurrence of an electrothermal switching cycle within any one of the stages may also be detected by sensing the heat dissipated from the thermistors in that stage. In FIG. 1, for example, a sensing thermistor TH1 is thermally coupled to the PTC thermistor P18 in the pair 18 for sensing the occurrence of an electrothermal switching cycle in that pair. As is apparent to those skilled in the art, the changes in resistance of thermistor TH1 may be employed to effect various programming operations. Since the sensing thermistor TH1 is not electrically connected to the electrothermal timing circuitry but is only thermally coupled thereto, it can be seen that electrical isolation can be maintained between the controlling and controlled circuits. Thermochromic paint may be employed to obtain a temperature responsive, visual indication of the sequencer's progress.

As there is a time delay between the operation of each successive stage, which delay depends upon the thermal characteristics of the constituent thermistors as noted previously, it can be seen that the apparatus of FIG. 1 is suited for timing, sequencing and programming applications, particularly those involving long intervals.

In the apparatus of FIG. 1, the thermistors which are thermally coupled to each other do not share a common connection and thus the thermal coupling must be arranged so as to maintain electrical isolation between the thermally coupled thermistors. As noted previously, however, each of the thermistor pairs may be run on D.C. of either polarity or on A.C. The apparatus illustrated in FIG. 6 is similar to that illustrated in FIG. 1 and comprises a plurality of pairs of thermistors 31-38, each pair including a PTC thermistor, P31-P38 respectively, and an NTC thermistor, N31-N38 respectively. In this construction, however, every other pair is reverse-connected with respect to the supply leads L1, L2. Thus, the thermistors of opposite coefficient type which are thermally coupled together to provide the transfer of triggering energy now have a common electrical connection. For example, PTC thermistor P31 and NTC thermistor N32 which are thermally coupled together are also both connected to the supply lead L2. With this common electrical connection, the thermal coupling between the thermistors need not maintain electrical isolation and can be relatively easily provided by bringing the two thermistors into contact at their common electrical connection as in the construction illustrated in FIGS. 7 and 8.

Referring to FIGS. 7 and 8, the thermistors are assembled as a unit on a header 41 of the type conventionally used for mounting transistors. Three leads 43, 45 and 47 extend through insulating hermetic seals in the header. A small block 49 of PTC thermistor material is soldered to a somewhat larger block 51 of NTC material as indicated at 53 and lead 43 is also soldered to this interface. Lead 45 is soldered to the outside surface of the block 51 while the lead 47 is soldered to the outside surface of the PTC block 49. As may be seen, this construction provides all of the required electrical connections while affording good thermal coupling between the two blocks of thermistor material. It should be noted that the two thermistors which are thus assembled as a unit do not constitute a single electrothermal switching stage or pair, but rather the two thermistors are component parts of two adjacent pairs in the sequencer of FIG. 6.

As noted previously, the behavior of an NTC thermistor with respect to changes in current is in many ways analogous to the behavior of a PTC thermistor with respect to changes in voltage. Accordingly, the roles of these thermistors in timing apparatus according to the present invention may be, in a sense, interchanged if parallel and series connections are similarly interchanged and if the resultant pairs are operated on substantially constant current rather than substantially constant voltage. Similar changes must also be made in the sequence initiating and feedback circuits.

A sequencer constructed according to this analogy is illustrated in FIG. 9. This apparatus comprises four pairs of thermistors 61-64. Each such pair or stage includes a PTC thermistor, P61-P64 respectively, electrically connected in parallel with an NTC thermistor, N61-N64 respectively. The parallel connection of PTC thermistor P61 with NTC thermistor N61 is completed through one side of a S.P.D.T. switch SW3 for a purpose described hereinafter. The NTC thermistors N61-N63 in the pairs 61-63 are thermally coupled to the PTC thermistors P62-P64 respectively, as indicated by the broken lines linking thermally coupled thermistors. The PTC thermistor P61 in the first pair 61 is thermally coupled to an NTC triggering thermistor NT which is connected in parallel with a voltage limiting resistor R3 and a normally closed pushbutton switch PB3 to constitute a triggering circuit 65. The NTC thermistor N64 in the last pair 64 is thermally cou-

pled to a PTC feedback thermistor P61A. Feedback thermistor P61A may be selectively placed in series with the PTC thermistor P61 in the first pair 61 by reversing switch SW3.

The thermistor pairs 61-64 and the triggering circuit 65 are connected in series across a pair of supply leads L5 and L6 for providing substantially constant current to the pairs. Leads L5 and L6 may be connected to a conventional constant current source although, as understood by those skilled in the art, a series connection of a large number of units such as the pairs 61-64 will inherently cause each unit to be supplied with essentially constant current despite nominal variations in the resistance of that one unit. The parallel-connected thermistors of opposite temperature coefficient types are essentially current-coupled in that, if the current passing through one of them changes for any reason, the current through the other must change in complementary fashion in order to maintain the total current at the predetermined constant level.

According to a presently accepted theory, the electro-thermal switching operation of each one of the pairs 61-64 proceeds substantially as follows. The pair 61 is taken as an example and it is assumed that the switch SW3 is in the position shown. Assuming that the level of current is appropriately adjusted, the pair will normally remain in a quiescent state with both thermistors being relatively cool. In this state the PTC thermistor P61 has a relatively low resistance so that it conducts most of the substantially constant current provided from the source.

If the PTC thermistor P61 is heated by a source external to the pair, e.g., by operating switch PB3 to cause triggering thermistor NT to heat, this heating has the effect of lowering the peak of the curve shown in FIG. 4 so that the current being carried by PTC thermistor P61 is sufficient to drive it into the negative resistance region and to cause it to regeneratively self-heat. The PTC thermistor P61 self-heats toward its transition temperature where its resistance increases sharply. As the resistance of the PTC thermistor increases, the voltage across the parallel-connected thermistor pair increases so that the voltage across the NTC thermistor surpasses the peak in its voltage/current characteristic, thereby causing it to also self-heat regeneratively. Heat generated in the NTC thermistor N61 is coupled to the PTC thermistor P62 in the next stage or pair and initiates an electrothermal switching cycle in that pair starting with a self-heating phase of PTC thermistor P62. The heat generated by PTC thermistor P62 is coupled back to the NTC thermistor N61 which triggered it and the total heat applied to and generated within NTC thermistor N61 causes its resistance to drop to a low level. The drop in resistance in thermistor N61 causes it to shunt current away from the PTC thermistor, thereby stopping the regenerative self-heating of the PTC and allowing it to revert to its original stable state. As the PTC thermistor reverts, its dropping resistance reduces the voltage across the NTC thermistor, so that the NTC thermistor also can no longer regeneratively self-heat and thus also reverts to its original stable state. This quiescent condition of the pair will then last until the pair is again triggered by applying external heat to the PTC thermistor.

The thermal coupling between the NTC thermistors in pairs 61-63 and the PTC thermistors in pairs 62-64 causes the occurrence of self-heating phase in one of those NTC thermistors to trigger or initiate an electrothermal switching cycle in the next stage or pair. Thus, once a sequence of electrothermal operations is triggered by the heating of thermistor NT, it propagates through the entire series of thermistor pairs.

The sequence of operations of the apparatus shown in FIG. 9 can be caused to repeat indefinitely by reversing the position of switch SW3 thereby placing the feedback thermistor P61A in series with the PTC thermistor P61 of the first pair 61. As both of the thermistors P61 and

P61A have a low resistance when cool, the main portion of the constant supply current must still flow through this arm of the parallel circuit when the stage is in its quiescent stage, and thus thermistor N61 will not self-heat unless this stage is triggered. However, an increase in resistance in either of thermistors P61 or P61A, such as may be produced by external heating, will initiate an electrothermal switching cycle of operation as previously described. The untriggered one of the two PTC thermistors P61 or P61A will not significantly interfere with the switching operation involving the other thermistor since the untriggered thermistor at all times remains at a low impedance level. Accordingly it can be seen that, when the last of the pairs (64) passes through its electrothermal cycle, the self-heating phase of NTC thermistor N64 will trigger an electrothermal cycle in the first stage 61 by applying heat to the PTC feedback thermistor P61A. Thus the circuit of FIG. 9 will function in the manner of a ring counter or ring pulser. For control, programming or indication purposes, the stage which is operating at any given moment can be detected or sensed in the various manners described previously with reference to FIG. 1. That is, the current through a thermistor may be sensed, the voltage across thermistor pairs may be sensed, or the heat dissipated from one of the thermistors may be sensed to effect electrically isolated signal coupling.

While the operations of the various embodiments have been explained with reference to a theory of operation 30 which assumes a bistable mode of operation, it should be understood that pairs of thermistors according to this invention may also be constructed to behave according to a so-called monostable or one-shot mode of operation in which the stage of itself reverts to its original condition 35 a predetermined interval after being triggered.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

What is claimed is:

1. Electrothermal timing apparatus comprising:
a plurality of pairs of pairs of thermistors, one of the thermistors in each of said pairs being of a first temperature coefficient type and the other of said thermistors being of opposite temperature coefficient type, at least one of said thermistors having a negative resistance region of operation;
circuit means interconnecting the thermistors in each pair with each other to provide electrical coupling therebetween and for interconnecting each of said pairs of thermistors with an electric power source whereby heating of the thermistor of said first coefficient type in one of said pairs will initiate an electro-thermal cycle in which said one and then said other of said thermistors in said one pair pass through self-heating phases in sequence;
means for thermally coupling the thermistor of said opposite coefficient type in a first one of said pairs to the thermistor of said first coefficient type in a second one of said pairs whereby the occurrence of an electrothermal cycle in said first pair of thermistors will initiate an electro-thermal cycle in said second pair of thermistors.

2. Timing apparatus as set forth in claim 1 wherein the thermistors in each pair are connected in series thereby providing voltage coupling therebetween.

3. Timing apparatus as set forth in claim 2 wherein said pairs of thermistors are connected in parallel across an electric power source providing a substantially constant voltage to each of said pairs.

4. Timing apparatus as set forth in claim 1 wherein the thermistors in each pair are connected in parallel thereby providing current coupling therebetween.

5. Timing apparatus as set forth in claim 4 wherein said pairs of thermistors are connected in series to an electric power source providing a substantially constant current to each of said pairs.

6. An electrothermal sequencer comprising:
a plurality of pairs of thermistors, one of the thermistors in each of said pairs being of a first temperature coefficient type and the other of said thermistors being of opposite temperature coefficient type, at least one of said thermistors having a negative resistance region of operation;

10 circuit means interconnecting the thermistors in each pair with each other to provide electrical coupling therebetween and for interconnecting each of said pairs of thermistors with an electric power source whereby heating of the thermistor of said first coefficient type in one of said pairs will initiate an electrothermal cycle in which said one and then said other of said thermistors in said one pair pass through self-heating phases in sequence;

15 means for thermally coupling the thermistor of said opposite coefficient type in all but one of said pairs to the thermistor of said first coefficient type in respective ones of the other pairs thereby defining a series of said pairs whereby the initiation of an electrothermal cycle in the first one of said pairs of thermistors in said series will initiate a sequence of 20 electro-thermal cycles in the other pairs of thermistors in said series.

25 7. An electrothermal ring counter comprising:
a plurality of pairs of thermistors, one of the thermistors in each of said pairs being of a first temperature coefficient type and the other of said thermistors being of opposite temperature coefficient type, at least one of said thermistors having a negative resistance region of operation;

30 circuit means interconnecting the thermistors in each pair with each other to provide electrical coupling therebetween and for interconnecting each of said pairs of thermistors with an electric power source whereby heating of the thermistor of said first coefficient type in one of said pairs will initiate an electro-thermal cycle in which said one and then said other of said thermistors in said one pair pass through self-heating phases in sequence;

35 40 means for thermally coupling the thermistor of said opposite coefficient type in each of said pairs to the thermistor of said first coefficient type in a respective one of the other pairs whereby the initiation of an electro-thermal cycle in one pair of thermistors will initiate a repeating sequence of electro-thermal cycles in said pairs of thermistors.

45 45 8. Apparatus as set forth in claim 7 including switch means for selectively breaking the interconnection between the thermistors in one of said pairs of thermistors to provide a predetermined point of interruption of said sequence.

9. Electrothermal timing apparatus comprising:
a plurality of pairs of thermistors, each pair including a PTC thermistor in series with an NTC thermistor, at least said PTC thermistor having a negative resistance region of operation;

5 circuit means connecting each of said pairs across a source providing a substantially constant voltage whereby heating of the NTC thermistor in one of said pairs will initiate an electro-thermal cycle in which the NTC thermistor and then the PTC thermistor in that pair pass through self-heating phases in sequence;

means for thermally coupling the PTC thermistor in each of a plurality of said pairs to the NTC thermistor in a respective other one of said pairs thereby defining a series of said pairs whereby the initiation of an electro-thermal cycle in the first one of said pairs in said series will initiate a sequence of electro-thermal cycles in the other pairs in said series.

10. Timing apparatus as set forth in claim 9 wherein said PTC thermistor has a resistance characteristic having a transition temperature above which the resistance of said PTC thermistor rises relatively abruptly.

11. Electrothermal timing apparatus comprising:
a plurality of pairs of thermistors, each pair including a PTC thermistor in parallel with an NTC thermistor, at least said PTC thermistor having a negative resistance region of operation;

15 circuit means connecting said pairs in series across a source thereby to provide a substantially constant current through each pair whereby heating of the PTC thermistor in one of said pairs will initiate an electro-thermal cycle in which the PTC thermistor and then the NTC thermistor in that pair pass through self-heating phases in sequence;

means for thermally coupling the NTC thermistor in each of a plurality of said pairs to the PTC thermistor in a respective other one of said pairs thereby defining a series of said pairs whereby the initiation of an electro-thermal cycle in the first one of said pairs in said series will initiate a sequence of electro-thermal cycles in the other pairs in said series.

12. Timing apparatus as set forth in claim 11 wherein said PTC thermistor has a resistance characteristic having a transition temperature above which the resistance of said PTC thermistor rises relatively abruptly.

UNITED STATES PATENT OFFICE
CERTIFICATE OF CORRECTION

Patent No. 3,457,429 Dated July 22, 1969

Inventor(s) Francis P. Buiting

It is certified that error appears in the above-identified patent and that said Letters Patent are hereby corrected as shown below:

In the heading to the printed specification, line 4, for "(34 Forest St., Attleboro, Mass. 02703)" read --assignor to Texas Instruments Incorporated, Dallas, Tex., a corporation of Delaware--
